CIGARETTE AND NECKTIE HOLDER

Harold H. Gardian, Akron, Ohio

Application August 4, 1936, Serial No. 94,242

3 Claims. (Cl. 131—51)

This invention relates to a cigarette and necktie holder and it aims to provide a novelty selectively usable to hold a cigarette or to secure the free ends of a necktie to the shirt.

5 It is particularly aimed to provide a holder for a cigarette, which may be attached to a finger, to hold the cigarette in such a manner that it will not stain or soil the fingers and will overcome the temptation to lay the cigarette in a dangerous position on a desk, among papers or otherwise.

10 It is further aimed to provide such a construction as will be adaptable to fingers of various sizes.

15 Various additional objects and advantages will become apparent from a consideration of the description following taken in connection with accompanying drawing illustrating an operative embodiment.

In said drawing:—

20 Figure 1 is a view of the device in extended position for holding a cigarette;

Figure 2 is a view of the device in the condition of Figure 1 taken at a right angle thereto;

25 Figure 3 is a vertical sectional view taken on the line 3—3 of Figure 2;

Figure 4 is a vertical sectional view taken on the line 4—4 of Figure 1;

Figure 5 is a detail section taken on the line 5—5 of Figure 1;

30 Figure 6 is a detail view of a modified form, partly in elevation and partly in section, showing a means for snug engagement with the finger, and

Figure 7 is a detail side elevation of a second modified form of means for maintaining snug

35 engagement with the finger.

Referring specifically to the drawing wherein like reference characters designate like or similar parts, the device comprises a pair of arms 10 and 11 which are interfitting and pivotally connected to a coupling member 12 of H-shaped, the pivots being designated 13 and 14. A spring leaf or plate 15 is fastened at 16 to the coupling 12 and it serves to hold the arms 10 and 11 in alignment or folded together in parallelism.

40 The arm 10 is equipped with a ring 18 adapted to be engaged by a finger and to better maintain it on the finger, the interior thereof is preferably serrated or knurled as at 19.

The arm 11 by means of a band 20, or otherwise, mounts a cigarette holder 21, having a draft passage 22 therethrough and an enlarged holder space at 23 in which the cigarette or cigar is wedged or mounted.

45 With the parts in the position of Figures 1 and 2 and the ring 18 worn on one of the fingers, a

cigarette is engaged in the portion 23 and it is always in a convenient position to be brought by the finger engaged by the ring 18, to the mouth of the smoker. This is much more convenient than having to lay the cigarette down from time to time onto a table or other support and which often increases the fire hazard, soils the fingers and is generally more objectionable than through the use of my device.

5 It is obvious that the arms 10 and 11 and all of the other parts may be made of any desired metal, other materials, or ornamented as preferred.

The invention not only serves as a cigarette or cigar holder, but it is adapted for use as a necktie holder. Because of the pivotal connection of the arms 10 and 11 and their engagement with the spring 15, the arms may be moved into substantial parallelism, and resiliently held in that condition by the spring 15. In such condition, it is in effect a clamp when the necktie is engaged, together with a portion of the shirt of the wearer, between the arms 10 and 11 and between the ring 18 and holder 21, to clamp the necktie to the shirt of the wearer.

20 Various changes may be resorted to within the spirit and scope of the invention. For instance, a modified form of ring may be used at 18', in lieu of the ring 18 as shown in Figure 6. In such figure, a plate 24 is located within the ring 18', being suspended by a coil spring 25, fastened to a cross pin 26 on the arm 10', equivalent to the arm 10. When the ring 18' is engaged with the finger, the latter also engages the plate 24, moving the latter against the tension of the spring 25, whereby the ring will be effectively resiliently held on the finger.

25 Another modification is shown in Figure 7 wherein the ring 18'' functions like that at 18 and 18'. In this instance, an arcuate spring 27 is located within the ring 18'' and by means of a clip 28 or otherwise, is fastened to the latter ring. Thus the finger will be engaged with the arcuate side of the spring 27 and the interior of the ring 18'' to better secure the ring in place on the finger.

30 I claim as my invention:—

1. An article of the class described having arms, means on one of the arms to mount the same on a finger, a cigarette holder carried by the other arm, and means connecting the arms for operative disposition in alignment or in folded position in substantial parallelism to form a clamp.

35 2. An article of the class described having arms, means on one of the arms to mount the same on a

finger, a cigarette holder carried by the other arm, and means connecting the arms for operative disposition in alignment or in folded position in substantial parallelism to form a clamp, 5 the first mentioned means being a ring, said cigarette holder and ring being opposite each other in the folded condition of the device.

3. An article of the class described having arms, means on one of the arms to mount the same on a 10 finger, a cigarette holder carried by the other

arm, and means connecting the arms for operative disposition in alignment or in folded position in substantial parallelism to form a clamp, 5 said second means comprising an H-shape coupling to which the arms are pivoted, and a spring mounted by said coupling and engageable by the adjacent ends of the arms to hold them in alignment or folded.

HAROLD H. GARDIAN. 10
